Patented Mar. 30, 1915

UNITED STATES PATENT OFFICE.

JAMES F. O'BRIEN, OF LOS ANGELES, CALIFORNIA.

AUTOMOBILE-LOCK.

1,133,393.

Specification of Letters Patent. Patented Mar. 30, 1915.

Application filed March 7, 1914, Serial No. 823,192. Renewed February 23, 1915. Serial No. 10,122.

To all whom it may concern:

Be it known that I, JAMES F. O'BRIEN, a citizen of the United States, residing at Los Angeles, in the county of Los Angeles, State of California, have invented new and useful Improvements in Automobile-Locks, of which the following is a specification.

This invention relates to an improved form of lock for motor vehicles, automobiles, 10 motorcycles, bicycles, etc. I herein explain the full application of my improved lock to an automobile; but it will be understood that the lock itself is the subject of the present invention, and that the lock may be applied to uses other than to locking automobiles and motor vehicles, etc.; although its 15 primary advantages are most obvious in connection with an automobile.

There are several prime features which I 20 wish to particularly emphasize, including the co-axial placement of the tumbler and of the locking disk, the concentric arrangement of the means for operating the tumbler and disk, the combination of the tumbler and disk and the simple stump and dog combination for holding the disk from movement; so that the whole lock is reduced to small size and at the same time its operation 25 is made dependable and efficient.

Another feature of importance is the independence of the tumbler and locking disk, to the extent that the manipulation of the tumbler to unlock the lock does not necessarily cause the operation of the locking disk (and does not cause the unlocking of the 30 hood). This is fully explained hereinafter.

I have illustrated a preferred embodiment of my invention in the accompanying drawings, in which,

40 Figure 1 is a longitudinal section of my improved lock, Fig. 2 is a section taken as indicated by line 2-2 of Fig. 1, Fig. 3 is a section taken as indicated by line 3-3 of Fig. 1, Fig. 4 is a view illustrating the application of my lock to an automobile, Fig. 5 is a view showing the hood locking means.

In the drawings, the numeral 10 may designate the dash of an automobile, and 11 may designate the casing of my lock mounted thereon, the dash forming the forward part of the casing. This casing 11 has a central wall or web 12 with a bearing 13 at its central part, this bearing 13 carrying the hub 14 of the flat disk tumbler 15. This 50 flat disk tumbler 15 is of a type well known to the art, its rear face having various ribs

16 thereon of different shapes, acting as cams to shift the stump pin 17 and the stump lever 18 between the positions shown in full and dotted lines in Fig. 2. Rotation 60 of the tumbler 15 is accomplished through the medium of a shaft 20 extending rearwardly from a thumb disk 21 which projects from the dash 10. This thumb disk 21 may carry a disk 22 having notches 23 in 65 its periphery, a flat spring 24 engaging these notches to form a "clicker" to indicate the rotation of the tumbler 15. When the tumbler 15 has been rotated back and forth in a pre-determined manner, the stump lever 18 will be forced to the position shown in dotted lines in Fig. 2. The stump lever is mounted upon a shaft 25, which shaft also carries a dog 26. This dog 26 is adapted to engage against a shoulder 27 on the rotatable locking disk 28 to prevent movement of the disk in the direction indicated in Fig. 3, which disk is mounted with its hub 28^a upon the outside of the bearing 13 carried by web 12. The disk 28 and the tumbler 15 are co-axial. A hollow sleeve 29 engages the disk 28 on its inner end and carries on its outer end a manually engageable handle 30 depending below the thumb disk 21. The sleeve 29 is flattened or otherwise 75 formed for engagement with the disk 28 so that the disk and sleeve must turn together. See Fig. 3. When the dog 26 has been moved to the position shown in dotted lines in Fig. 3, then the locking disk 28 may be 80 turned in the direction indicated by turning the handle 30. But it will be understood that the manipulation of the tumbler does not directly cause or necessitate movement of the locking disk. Removal of the dog 85 26 only permits movement of the locking disk, which may then be moved at will. Turning the disk 28 in the direction indicated causes movement of the connecting rods 31 in the direction indicated and causes the unlocking 90 of the hood 32 which uncovers the engine 33. Rods 31 are connected to studs 31^a mounted on the locking disk 28; and holes 31^b are provided so that the studs may be set in any position depending on the direction 95 the rods 31 take to reach the hood locking mechanism. Stop 31^c may limit the movement of the locking disk in the direction opposite to that indicated; although it will be seen that the rods 31 throw over 100 against the hub 28^a and form effectual stops to the disk movement.

The mechanism for locking the hood 32 may be of any preferred character; I may use a plurality of movable hooks 34 which engage with corresponding hooks 35 upon inside of the hood, the hooks 34 being mounted upon longitudinal shafts 36, which are operated by the connecting rods 31. The lower edges of the hood may be guided to correct position and prevented from moving outwardly by suitable stops constructed, 10 as is best shown in Fig. 5, with plates 36^a with upturned edges 37 secured to the frame of the automobile by bolts 38. The upturned edges bear against the sides of the bolt heads to prevent the bolt heads being turned without also turning the plates 36^a; and when the hood is locked down the plates 36^a cannot be turned owing to the engagement of the hood with their upturned edges 37. 15 It will thus be seen that the hood cannot be opened unless the lock is manipulated according to the correct combination, which can only be done by authorized persons. But the hood need not be unlocked unless so wished. It will be noted that the rods 31 extend in such directions that their pull on the studs 31^a tends to rotate the disk 28 opposite to the direction indicated; that is, the studs 31^a "throw over center" with respect to the pull on the rods 31. So that, when the dog 26 is retracted, there is no tendency for the disk to move in the direction indicated unless the handle 30 is moved. The lock may be manipulated (by an authorized person only) to connect the ignition circuits without loosening the hood lock. This provision makes it possible to do away with all the usual devices for holding down the hood, my device completely supplanting them. I provide also certain switches which control the electric ignition of the engine which is locked under the hood. The general arrangement of these switches in the ignition circuit is not necessary to be herein described; I particularly describe the switches in their combination with my lock mechanism. There is one switch which comprises a contact base 40 adapted to be engaged by the lever 18 when in one of its positions, 20 this being a switch which will ground a current on the wire 41 when the lock is in the proper corresponding position. I also provide a switch which makes and breaks the circuit between two wires 42 and 43. This switch may comprise a sliding contact piece 44 connected at 45 with the lever 18 and in normal engagement with the contact 46. Movement of the lever 18 causes movement of the end 44^a of contact 44 into engagement 25 with the contact 47 completing the circuit between wires 42 and 43. The frictional engagement of the lever 18 with these switches, and the friction of the moving contact 44 with the contacts 46 and 47, is sufficient to hold the lever 18 and the dog 26 in

any position to which they are moved by the action of the tumbler. The switches thus perform a function which is usually performed by a spring or other member bearing against the lever 18. The switches are connected into the ignition circuit of the engine 33 in such a manner that when the lock is "locked" (the lever 18 being in the position shown in full lines) no current can be obtained for ignition of the engine charges. 70 At the same time the hood is locked down so that it is impossible for an unauthorized person to reach the wiring system covered by the hood to tamper with it. The machine is thus securely and positively locked 80 against theft.

I herein explain the application of my lock to an automobile in order to most clearly point out its advantages; in the following claims I particularize on the improvements in the locking mechanism. It is broadly immaterial what work the locking disk 28 does; it may operate locking mechanisms of any character, although, as explained, it is particularly adapted for the 90 functions described.

I claim—

1. A lock of the character described, comprising a case, a manually rotatable tumbler therein, a pivoted stump lever coöperating 95 with said tumbler, a rotatable locking disk co-axial with the tumbler and manually rotatable independently of the tumbler, and a pivoted dog connected with the pivoted stump and normally engaging the locking 100 disk to prevent its rotation.

2. A lock of the character described, comprising a case, a manually rotatable flat disk tumbler in the case, a stump lever pivoted within the case and adapted to oscillate 105 across one face of the tumbler, a locking disk co-axial with the tumbler and adjacent thereto and manually rotatable independently of the tumbler, and a dog mounted upon the tumbler axis and moving therewith and coöperating with the locking disk to prevent its movement, the arrangement being such that the stump lever and dog may be moved by manipulation of the tumbler 110 to release the locking disk.

3. A lock of the character described, comprising a case, a manually rotatable flat disk tumbler therein, a locking disk co-axial with the tumbler and manually rotatable independently of the tumbler, independent concentric means for manually independently rotating said tumbler and disk, a pivoted stump lever coöperating with the tumbler, and a dog mounted on the stump lever pivot 120 to move therewith adapted to engage the locking disk to prevent its movement.

4. A lock of the character described, comprising a case, a manually rotatable flat disk tumbler therein, a manually rotatable flat locking disk co-axial with the tumbler, 130

a hollow sleeve connected with the locking disk and extending without the case, a manually engageable handle on the outer end of the sleeve, a shaft contained within 5 and concentric with said sleeve, said shaft being rotatable independently of the sleeve and connected with the tumbler on its inner end and having a manually engageable hand disk on its outer end; a stump lever axis 10 parallel to the axis of the tumbler and the locking disk, a stump lever mounted upon the axis and adapted to move across the face of the tumbler opposite the locking disk, a shoulder on the locking disk, and a dog 15 mounted upon the stump lever axis to move therewith to engage and disengage the shoulder on the locking disk.

5. A lock, comprising in combination a case, a rotating tumbler therein, a rotatable locking disk concentric with the tumbler, 20 the tumbler and disk being independently rotatable, and a dog operated by the tumbler and engaging the disk to prevent its rotation, the arrangement being such that the dog may be moved by manipulation of the 25 tumbler to release the disk for movement.

In witness that I claim the foregoing I have hereunto subscribed my name this 27 day of February 1914.

JAMES F. O'BRIEN.
